(57) **CLAIM**

The ornamental design for a meat chopper as shown and described.

DESCRIPTION

FIG. 1 is a front, left and top perspective view of a meat chopper, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, left and top perspective view of the meat chopper, shown in use with environmental structure.

The dashed broken lines in the drawings depict portions of the meat chopper and environmental subject matter, specifically the base in FIG. 9, that form no part of the claimed design.
